UNITED STATES PATENT OFFICE.

ALBERT P. NEBE, OF GARY, INDIANA.

PACKAGE.

Application filed December 24, 1924. Serial No. 757,924.

This invention relates to the packaging of sheets and plates, and more particularly to an improved and novel package for packaging tin plate and the like.

5 Heretofore it has been the practice to pack tin plate in wooden crates or boxes, each of which held 112 sheets, which was equivalent to one or more base boxes, a base box of tin plate being equal to 112 sheets 20 by 14 10 inches. Generally sheets of tin plate are now made in larger sizes, that is, 20 by 28 inches or more and, therefore, 112 sheets will equal two or more base boxes. A base box of sheets will weigh anywhere from approximately 15 50 pounds to 250 pounds or more, according to gage and, therefore, it will be readily appreciated that an enormous amount of manual labor must be utilized to handle the packages of tin plate as heretofore made, 20 especially when loading into and unloading such packages from railway cars.

One object of the present invention is to reduce the manual labor necessary in handling packages of tin plate to a minimum.

25 Another object is to provide a novel form of package which will contain a plurality of base boxes of sheets, weighing anywhere from a few hundred pounds to a ton or more, may be readily packaged and assembled, and 30 especially adapted for mechanical loading into and unloading from a railway car.

Another and important object is to provide a package which, due to its novel construction, will not crush under extreme loads 35 of forty to fifty tons, as for instance when several of the packages are piled one on top of the other as in a warehouse.

A further object is to provide a novel package for tin plate which will materially 40 reduce the tare weight of the packages, thus resulting in a material saving in shipping cost.

A still further object is to provide a novel package for packaging sheets and plates having the novel construction, as clearly described in the following specifications and illustrated in the accompanying drawings.

In the drawings—

50 Figure 1 is a side elevation of a package of sheets or plates packed in accordance with this invention.

Figure 2 is an end elevation of the same.

Figure 3 is a sectional elevation taken on line III—III of Figure 1.

55 Referring more particularly to the draw-

ings, the numeral 2 designates the base or platform portion of the package, which is of rectangular shape and generally composed of wood. A plurality of supporting strips or legs 3 are secured by nailing, or otherwise, 60 to the bottom face of the platform or base member 2 so as to support the base slightly above the floor for a purpose to be described.

The base 2 is of slightly greater length and width than the sheet or plates to be packed 65 so as to permit the plate to be piled thereon in other than perfect vertical alignment, but said base is of less length and width than the cover member B, for a purpose to be described.

70 The cover member B, comprises a top 6, sides 7 and 8, and ends 9 and 10, all secured firmly together by nailing or the like.

The cover member B is of such size as to readily fit down over the piled sheets or 75 plates and the base 2 so that its top 6 will rest directly on the pile of sheets.

The cover member B and base member 2 are adapted to be detachably secured together by flexible straps or bands of wire 11 80 or the like. It will be understood that while only two wire bands are shown, both of which go around the package in the same direction, that any number of bands desired may be used, and if necessary or preferable, other bands may be passed around the package in the opposite direction to the bands shown.

85 In carrying out my invention, a plurality of bundles or base boxes A of sheets or plates, each consisting of 112 sheets and weighing from fifty to two hundred and fifty pounds each, are piled on the base 2, one on top of the other until a suitable quantity (generally approximately one ton) 90 is obtained to fill the package. The cover B is then raised above the piled sheets and then lowered over the pile of sheets until its lower edge projects below the base 2, and its top 6 rests upon the top of the pile of 95 sheets or plates.

100 The tie wires or bands 11 are then passed under the base 2 and over the cover B and have their ends twisted or otherwise secured together so as to detachably secure the cover 105 B and base 2 together.

Packages formed as set forth above will not crush when piled in warehouses or other places even when piled in piles of forty or fifty high at which times the bottom pack-

age will have from forty to fifty tons load on it, since the cover member is supported on the pile of sheets in the package and is free to move relative to the base 2 and so deliver the whole load onto the sheets and base. It will also be noted that horizontal movement of the cover B relative to the base 2 is prevented due to the fact that the cover extends down over the base and is tied by the 10 wires or bands 11.

With a package thus formed it may be readily moved around the plant or loaded into a car by a tractor having a suitable forked load carrying element adapted to pass under the elevated base 2, or a suitable sling may be readily passed under the package and a crane used to move the package from place to place or to pile it.

When the car containing the package is 20 delivered to the purchaser, if he does not have a tractor, the wires or bands 11 are cut and the cover B lifted up and the plate unloaded by hand.

This method of packaging sheets and 25 plates will provide a great saving in labor, reduce the cost of packaging, and reduce the cost of freight, since there will be materially less tare weight.

While I have shown and described only 30 one specific embodiment of my invention, various modifications may be made without departing from the scope of my invention as defined in the appended claims.

I claim—

35 1. A package for sheets and plates, comprising a flat platform-like base, means for supporting the base in spaced relation above the ground, a rigid cover member composed of sides, ends and top, assembled and all 40 permanently secured together, said cover member being of such size that it will telescope said base when positioned over the sheets or plates and rest directly on the sheets or plates, and means encircling said

base and cover member for securing said 45 base and cover together.

2. A package of sheets or plates, comprising a base means for supporting the base in spaced relation above the ground, a plurality of base boxes of sheets or plates piled on said 50 base, a cover member composed of sides, ends and top, all rigidly secured together, said cover being of greater length and width than said sheets or plates and said base and being adapted to be lowered bodily over the 55 sheets or plates until its top rests upon the top of said pile of sheets or plates, and means for detachably securing said cover in place, said means being such as to permit downward movement of said cover when 60 load is applied to the top thereof such as by piling packages one on top of the other.

3. A package of sheets or plates, comprising a base means for supporting the base in spaced relation above the ground, a 65 plurality of base boxes of sheets or plates piled on said base, a cover member composed of sides, ends and top, all rigidly secured together, said cover being of greater length and width than said sheets or plates and 70 said base and of greater depth than the pile of sheets or plates, and being adapted to be lowered bodily over the sheets or plates until its top rests upon the top of said pile of sheets or plates and its sides and ends project below said base, and a plurality of tie members passed under said base and over said cover for detachably securing said cover to said base, said cover being free to move downward relative to said base when load 75 80 is applied to the top of the cover, such as by piling packages one on top of the other, thereby preventing crushing of the cover or base.

In testimony whereof, I have hereunto 85 signed my name.

ALBERT P. NEBE.
